[57] CLAIM

The ornamental design for a refuse container, as shown and described.

DESCRIPTION

FIG. 1 is a frontal perspective view of a refuse container showing my new design, a rear perspective view being identical thereto;

FIG. 2 is a left side elevational view thereof; a right side elevational view being identical thereto; and.

FIG. 3 is a top plan view thereof.

The bottom of the refuse container is plain and unornamented.

FIG. 2FIG. 3
